SOUND PRODUCING DEVICE FOR
SIGNALING PURPOSES

Robert E. Swanson, Vancouver, British Columbia,
Canada, assignor, by mesne assignments, to
Nathan Manufacturing Corp., a corporation of
New York

Application March 28, 1950, Serial No. 152,333

16 Claims. (Cl. 116—142)

1

This invention relates to improvements in a sound producing device for signalling purposes and particularly to pneumatic horns used on railway locomotives.

As usually constructed pneumatic horns of the multiple type point in one direction, namely to the front of the locomotive and, as most horns are inherently directional in their sound propagational qualities, it can be expected that horns will be more effective in the direction toward which they are pointing. In railroad signalling it is often desirable to have the sound of the horn carried far to the rear of the train to call flagmen, and when all the horns point in a forward direction their sound cannot be heard as well to the rear. To overcome this difficulty it has become necessary to install two separate and independently operated horns on a locomotive if the sound is to be carried in both directions. With the advent of multiple air horns using several horns constructed into one unit and used for forward signalling it would be unnecessary to install another separate horn pointing in the opposite direction if units of the existing group of horns could be reversed.

It is an object of this invention to provide a multiple air horn in which horns arranged on one base for unitary operation can be reversed so as to point in either or both directions.

Another object is to provide a multiple horn that when horns are reversed the overall length of the horn unit will not be excessively long.

A further object of the invention is to provide an improved multiple horn which incorporates air diffusing plates and removable horn seats in each diaphragm casing, which parts are held in place by assembly bolts used to attach the diaphragm casings to the base and which bolts are sealed within the diaphragm chambers.

A further object of the invention is to provide an improved horn which is simple in construction and can be produced in quantities at low cost.

Other objects of the invention and features of novelty will be apparent from the following description taken in connection with the accompanying drawing in which

Fig. 1 is a fragmentary horizontal sectional view of a double tone multiple horn with the horns pointing in opposite directions; dotted lines show the arrangement when both horns point in one direction;

Fig. 2 is a vertical sectional view, partly in elevation, along the plane of line 2—2 in Fig. 1;

Fig. 3 is a vertical sectional view, partly in

2

elevation, along the plane of line 3—3 in Fig. 2, showing reversible drilling and air porting in the base to which a diaphragm casing and horn bell may be attached to point in either direction.

5 It will be noticed the large center hole through the base casting forms a part of the horn chamber; and

Fig. 4 is a vertical sectional view, partly in elevation, along the plane of line 4—4 in Fig. 1.

10 Like characters of reference denote similar parts throughout the several views and the following specification.

Referring to Fig. 2, a substantially T-shaped base 10 is provided with a flange 11 at its central branch 12 for fastening it to a locomotive or other structure on which it is to be mounted. Side branches 13 of the base 10 terminate in cylindrically shaped ends 14, the walls of which are drilled for bolts 15. Each end 14 is provided with a central round aperture 16.

15 17 is a horn bell having a flange 18 which abuts a side of one of the ends 14 of the base 10 and is held there by the bolts 15. The outer end of the bell is flared at 19. The inside of the bell forms a resonant air chamber, its smallest portion being concentric with and forming a continuation of the central opening 16 through end 14 of the base.

20 18 is a diaphragm housing having a wall 21 abutting an opposite side of end 14 of the base 10 and which is held there also by bolts 15. 22 is a central opening through the wall 21 concentric with and of the same size as opening 16 in end 14 of the base. The outer portion of the diaphragm housing is enlarged to receive a cap 23 provided with a vent opening 23a and an inwardly extending annular projection 24 to clamp a flexible diaphragm 25 against a shoulder 26 within the housing. Cap 23 is fastened to the housing by screws 27. 28 are lugs on the cap and housing having holes 29 for the reception of a wire seal 30.

25 31 is an annular seat ring inserted into wall 21 of the housing 20, coaxial with opening 22 therein. Seat ring 31 is provided with a shoulder 32 where its outer diameter is slightly reduced. 33 is a circular diffuser plate seating against the shoulder 32 and held there by heads 34 of bolts 15 which as the drawings clearly show also connect together the diaphragm housing 20, base 10, and horn bell 17. The diaphragm 25 is adapted to seat upon the outer face of seat ring 31. The diameter of the diffuser plate 33 is slightly smaller than the inner diameter of the 30 housing 20 forming an annular orifice 35 between

them. Diffuser plate 33 divides that part of the housing 20 between diaphragm 25 and wall 21 into an air diffusing chamber 36 and an operating pressure chamber 37 in communication with each other only by means of orifice 35. 25a is a chamber between the outer surface of diaphragm 25 and cap 23 which is open to the atmosphere.

38 is an air port through the vertical central branch 12 of the base 10 connecting with a duct 39 in the horizontal side branches of the base. 40 are cross ducts through the walls of ends 14 of the base in communication with duct 39. Each cross duct 40 has one end closed by the flange 18 of the horn bell 17, while its other end is in communication with chamber 36 of the housing 20 by means of a port 41. Air can be admitted into the porting just described through either of openings 42 (shown plugged) in bosses 43 at the sides of the central branch 12 above the flange 14 whichever is most convenient. The air port 38 is blanked off at the bottom of the base by the flange 11 contacting the structure upon which the device is mounted. A tight seal is provided for between the abutting surfaces of diaphragm housing 20, base 10, and horn bell 17, to prevent the escape of air by either well machined surfaces or gaskets.

It will be noted that the inner part of seat ring 31, central opening 22 in the wall of housing 20, opening 16 in base 10, and the inside of horn bell 17 are aligned and form a continuous resonant air column terminating into the free atmosphere at the flared end of the bell and being closed at the other end by diaphragm 25. Such air columns with respect to resonance are governed by the natural laws which govern stopped organ pipes and are one-quarter wave length of their functional frequencies, the overtone harmonics being thirds, fifths and sevenths. These resonant air columns are of different lengths calculated to produce harmonious sounds when both horns are sounded together as outlined later.

It is not the purpose of this invention to limit the assembly of horns in one unit to any particular number, any number of horns of different frequencies in relation with each other may be attached to such a multiple base as herein explained or a single horn may be attached in the same manner. When for instance, three horns are attached they may be constructed with suitable horn bells and diaphragms to produce a musical chord in a major key and if it is desirable to change the key to a minor chord different horn bells and diaphragms may be substituted as all parts can be interchangeable with each other by this novel means of attachment.

Referring to Fig. 1, it will be noticed cap 23 is attached to diaphragm housing 20, holding diaphragm 25 in place by screws 27. This attachment can also be accomplished by threading cap 23 into housing 20; however a seal 30 is provided through lugs 28 which prevents the removal of cap 23 unless seal 30 is broken. By this means the heads of bolts 15 are also sealed so that the horns cannot be tampered with or its direction reversed unless the seal is broken.

Referring again to Fig. 1, as well as Fig. 3, if it becomes desirable to reverse the direction of a horn leaving the other horn (or horns) pointing in a forward direction, it is only necessary to break the seal 30, remove screws 27, lift out diaphragm 25, after which bolts 15 are removed, allowing housing 20 and horn bell 17 to be detached from end 14 of the base 10. Housing

20 is then interchanged with horn bell 17 so that housing 20 is on the right side and horn bell 17 on the left side after which bolts 15 are again tightened up. The horn is then in the position shown in Fig. 3.

Referring again to Fig. 1, it will be noticed that seat ring 31 is held in position by pressure exerted on diffuser plate 33 by bolts 15 when tightened against shoulder 32 of the ring. This is an advantage and an improvement over other horns in that the seat bushing is held rigid and can be renewed in the field without resort to special tools.

It will also be noticed that with the novel arrangement of assembly by using a portion of the base 10 to form a chamber 16 as a central portion of the horn bell 17 when a horn and diaphragm casing are reversed the overall length of the entire multiple horn unit is not doubled in length as would be the case if the housing 20 and cap 23, for instance, were integral parts of the base 10 and used to mount and support the horns, which latter system of mounting horns to point in one direction is well known in the art.

Operation

Referring to Figs. 1 and 2, air under pressure enters the manifold base 10 from a source of pressure supply and flows through one of the openings 42 into air port 38 where it enters duct 39 connecting with cross ducts 40. The air then flows through restricted ports 41 into chambers 36 where it impinges against diffuser plates 33 breaking its velocity and building up a pressure in chambers 36 so that air enters chambers 37 through thin annular orifices 35. Pressure in chambers 37 then builds up to a higher pressure than exists in chambers 25a which are connected to the atmosphere through vents 23a. As the pressure in chambers 37 continues to build up the diaphragms 25 are deflected into the chambers 25a displacing the air in chambers 25a to the atmosphere. When this occurs a circular puff of air is admitted into resonant air chambers formed by seat ring 31, base 10 and horn bell 17, suddenly releasing the pressure from chambers 37 and as diaphragms 25 are thin circular leaves of a spring-like nature calculated to vibrate on the natural frequencies of third, fifth and seventh harmonics of these air chambers vibration is set up in the diaphragms 25 which vibration is supported and strengthened by the resonance in the air chambers of the horns, which is transmitted to the atmosphere through amplifying flares 19 resulting in a very strong and powerful signal with a pleasing tone. As the velocity of air is increased undue turbulence is avoided in chambers 37 due to the air entering through the thin annular orifice 35 where oil and dirt is deposited as far away as possible from the seating surface on seat ring 31 and at the same time the direct impingement effect of air entering through ports 41 and striking the diaphragm 25 is avoided which impingement effect would have a tendency to distort the diaphragms 25 at high pressures with resultant high air velocities causing the horns to emit distorted notes when forced by high air pressures.

While the various embodiments of the improved reversible and multiple pneumatic horn provided by the invention have been illustrated and described in detail it should be understood that the invention is not limited to these details of construction and that numerous details and modifications may be made without departing from the scope of the following claims.

What I claim as new is:

1. In a sound producing device, a base, a diaphragm unit at one side of the base and a horn bell at the opposite side of the base, the base having a bore in continuation of the inside of the horn bell and forming a resonant air column therewith, one end of the column being closed by the diaphragm unit, the diaphragm unit and the horn bell being interchangeable.

2. In a sound producing device, a base, a diaphragm unit at one side of the base and a horn bell at the opposite side of the base, the base having a bore in continuation of the inside of the horn bell and forming a resonant air column therewith, one end of the column being closed by the diaphragm unit, the diaphragm unit and the horn bell being interchangeable, the base having ports for admitting fluid under pressure to the diaphragm unit irrespective of the position of the diaphragm unit on the base.

3. In a sound producing device, a base, a diaphragm unit mounted at one side of the base and a horn bell mounted at the opposite side of the base, the diaphragm unit and the horn bell being interchangeable, the base having ports for admitting fluid under pressure to the diaphragm unit, irrespective of the position of the diaphragm unit on the base, including a port having one end closed by the horn and its other end in register with a passage to the diaphragm unit.

4. In a sound producing device, a base, a diaphragm unit at one side of the base and a horn bell at the opposite side of the base, the base having a bore in continuation of the inside of the horn bell and forming a resonant air column therewith, one end of the column being closed by the diaphragm unit, and means operable from within the diaphragm unit to draw the unit, base and horn together.

5. In a sound producing device, a base, a diaphragm unit at one side of the base and a horn bell at the opposite side of the base, the diaphragm unit and the horn bell being interchangeable, means operable from within the diaphragm unit to draw the unit, base and horn together, and a seal locking the diaphragm unit whereby operating the means is prevented unless the seal is broken.

6. In a sound producing device, a base having a stem and branches extending therefrom, a plurality of sockets in the branches, a diaphragm unit at one side of each socket and a horn bell at the opposite side of each socket, each socket having a bore in continuation of the inside of the horn bell and forming a resonant air column therewith, one end of the column being closed by the diaphragm unit, the stem having ports for admitting fluid under pressure into a duct common to the branches and a conduit in each socket in communication with the duct having one end closed by the horn at one side of a socket and its other end in register with an opening in the diaphragm unit at the other side of the socket.

7. In a sound producing device, a diaphragm unit having a chamber, a seat ring projecting into the chamber, a flexible diaphragm mounted in the chamber and adapted to engage the projecting end face of the ring, a diffuser plate mounted over the projecting sides of the ring, the plate forming in the chamber with its peripheral edge a narrow annular orifice, the chamber having an inlet admitting fluid under pressure to that side of the plate opposite the side facing the diaphragm whereby the fluid is forced through the narrow annular orifice to operate the diaphragm.

phragm and then pass to within the seat ring, and a horn bell forming a resonant air chamber in continuation of the seat ring.

8. In a sound producing device, a diaphragm unit having a chamber, a seat ring projecting into the chamber having a shoulder, a flexible diaphragm mounted in the chamber and adapted to engage the projecting end face of the ring, a diffuser plate mounted over the projecting sides of the ring and resting against its shoulder, the plate forming in the chamber with its peripheral edge a narrow annular orifice, the chamber having an inlet admitting fluid under pressure to that side of the plate opposite the side facing the diaphragm whereby the fluid is forced through the narrow annular orifice to operate the diaphragm and then pass to within the seat ring, a horn bell forming a resonant air chamber in continuation of the seat ring, and common means holding the plate against the shoulder on the seat ring and the diaphragm unit to the horn bell.

9. In a sound producing device, a base, a diaphragm unit at one side of the base having a chamber, a seat ring projecting into the chamber having a shoulder, a flexible diaphragm mounted in the chamber and adapted to engage the projecting end face of the ring, a diffuser plate mounted over the projecting sides of the ring and resting against its shoulder, the plate forming in the chamber with its peripheral edge a narrow annular orifice, the chamber having an inlet admitting fluid under pressure to that side of the plate opposite the side facing the diaphragm whereby the fluid is forced through the narrow annular orifice to operate the diaphragm and then pass to within the seat ring, a horn bell at the other side of the base and interchangeable with the diaphragm unit forming a resonant air chamber in continuation of the seat ring, and common means holding the plate against the shoulder on the seat ring and drawing the diaphragm unit, base and horn bell together.

10. In a sound producing device, a base, a diaphragm unit at one side of the base and a horn bell at the opposite side of the base, the base having an opening in continuation of the inside of the horn bell and forming a resonant air column therewith, one end of the column being closed by the diaphragm unit, the unit having a chamber, a seat ring projecting into the chamber, a flexible diaphragm mounted in the chamber and adapted to engage the projecting end face of the ring, a diffuser plate surrounding the projecting sides of the ring, the plate forming in the chamber with its peripheral edge a narrow annular orifice, the chamber having an inlet admitting fluid under pressure to that side of the plate opposite the side facing the diaphragm whereby the fluid is forced through the narrow annular orifice to operate the diaphragm and then pass to within the seat ring, the inner part of the ring being a continuation of the resonant air column.

11. In a sound producing device, a base, a diaphragm unit at one side of the base and a horn bell at the opposite side of the base, the base having an opening in continuation of the inside of the horn bell and forming a resonant air column therewith, one end of the column being closed by the diaphragm unit, the unit having a chamber, a seat ring projecting into the chamber, a flexible diaphragm mounted in the chamber and adapted to engage the projecting end face of the ring, a diffuser plate surrounding the projecting sides of the ring, the plate forming in the chamber with its peripheral edge a narrow annular

orifice, the base having ports for admitting fluid under pressure to the unit through an inlet to the chamber to that side of the plate opposite the side facing the diaphragm whereby the fluid is forced through the narrow annular orifice to operate the diaphragm and then pass to within the seat ring, the inner part of the ring being a continuation of the resonant air column.

12. In a sound producing device, a base, a diaphragm unit at one side of the base and a horn bell at the opposite side of the base, the base having an opening in continuation of the inside of the horn bell and forming a resonant air column therewith, one end of the column being closed by the diaphragm unit, the unit having a chamber, a seat ring projecting into the chamber having a shoulder, a flexible diaphragm mounted in the chamber and adapted to engage the projecting end face of the ring, a diffuser plate surrounding the projecting sides of the ring and resting against its shoulder, the plate forming in the chamber with its peripheral edge a narrow annular orifice, the base having ports for admitting fluid under pressure to the unit through an inlet to the chamber to that side of the plate opposite the side facing the diaphragm whereby the fluid is forced through the narrow annular orifice to operate the diaphragm and then pass to within the seat ring, the inner part of the ring being a continuation of the resonant air column, and means operable from within the diaphragm unit holding the plate against the shoulder on the seat ring and drawing the diaphragm unit, base and horn bell together.

13. In a sound producing device, a base, a diaphragm unit at one side of the base and a horn bell at the opposite side of the base, the base having an opening in continuation of the inside of the horn bell and forming a resonant air column therewith, one end of the column being closed by the diaphragm unit, the unit having a chamber, a seat ring projecting into the chamber having a shoulder, a flexible diaphragm mounted in the chamber and adapted to engage the projecting end face of the ring, a diffuser plate surrounding the projecting sides of the ring and resting against its shoulder, the plate forming in the chamber with its peripheral edge a narrow annular orifice, the base having ports for admitting fluid under pressure to the unit through an inlet to the chamber to that side of the plate opposite the side facing the diaphragm whereby the fluid is forced through the narrow annular orifice to operate the diaphragm and then pass to within the seat ring, the inner part of the ring being a continuation of the resonant air column, means operable from within the diaphragm unit holding the plate against the shoulder on the seat ring and drawing the diaphragm unit, base and horn bell together, and a seal locking the unit whereby operating the means is prevented unless the seal is broken.

14. In a sound producing device, a base having

a stem and branches extending therefrom, a plurality of sockets in the branches, a diaphragm unit at one side of each socket and a horn bell at the opposite side of each socket, each socket having a bore in continuation of the inside of the horn bell and forming a resonant air column therewith, one end of the column being closed by the diaphragm unit, the units and the horn bells being interchangeable whereby the horn bells can be mounted pointing in opposite directions.

15. In a sound producing device, a base having a stem and branches extending therefrom, a plurality of sockets in the branches, a diaphragm unit at one side of each socket and a horn bell at the opposite side of each socket, each socket having a bore in continuation of the inside of the horn bell and forming a resonant air column therewith, one end of the column being closed by the diaphragm unit, the units and the horn bells being interchangeable whereby the horn bells can be mounted pointing in opposite directions, the stem having ports for admitting fluid under pressure into a duct common to the branches and a conduit in each socket in communication with the duct having one end closed by the horn at one side of a socket and its other end in register with an opening in the diaphragm unit at the other side of the socket.

16. In a sound producing device, a base having a stem and branches extending therefrom, a plurality of sockets in the branches, a diaphragm unit at one side of each socket and a horn bell at the opposite side of each socket, each socket having a bore in continuation of the inside of the horn bell and forming a resonant air column therewith, one end of the column being closed by the diaphragm unit, the units and the horn bells being interchangeable whereby the horn bells can be mounted pointing in opposite directions, the stem having ports for admitting fluid under pressure into a duct common to the branches and a conduit in each socket in communication with the duct having one end closed by the horn at one side of a socket and its other end in register with an opening in the diaphragm unit at the other side of the socket and means operable from within each diaphragm unit to draw a unit and a horn bell together with a socket between them.
